INVENTOR:
John F. Reilly
By his attorney
Charles J. Gooding

UNITED STATES PATENT OFFICE.

JOHN F. REILLY, OF SOMERVILLE, MASSACHUSETTS.

EYE FOR HANDLES AND THE LIKE.

1,260,709.

Specification of Letters Patent. Patented Mar. 26, 1918.

Application filed July 13, 1917. Serial No. 180,468.

To all whom it may concern:

Be it known that I, JOHN F. REILLY, a citizen of the United States, residing at Somerville, in the county of Middlesex and State of Massachusetts, have invented new and useful Improvements in Eyes for Handles and the like, of which the following is a specification.

This invention relates to improvements in eyes formed of sheet material and has for its object to provide a cheap, strong and durable eye adapted to be utilized as a handle or to have attached thereto strips of material, such as leather or the like, and which is so constructed that it will not cut or chafe the material attached thereto and when used as a handle it will present a smooth rounded surface to contact with the hand.

The invention consists in the combination and arrangement of parts set forth in the following specification and particularly pointed out in the claim.

Referring to the drawings:

Figure 1 is a side elevation of a pair of eyes each embodying this invention and connected together by a strip of sheet material constituting a handle.

Fig. 2 is a side elevation of an eye formed in accordance with this invention, shown attached to the end of a case and performing the function of a handle.

Fig. 3 is a section taken on the line 3—3 of Fig. 2.

Fig. 4 is a section through an eye embodying this invention, showing the same attached to the end of a strip of sheet material, such as a strap.

Fig. 5 is a section through an eye, illustrating how said eye may be attached to the top of a case to serve as a handle therefor.

Like numerals refer to like parts throughout the several views of the drawings.

In the drawings, referring particularly to Fig. 1, 6 and 7 represent eyes which are formed from sheet material, such as steel or fiber. This material is bent double at 8 or folded near the center thereof so that the two sections 9 and 10, formed by said fold, will be substantially coextensive and lie face to face for at least a portion of the area thereof. Each of the sections 9 and 10 is perforated at adjacent portions to form holes 11, 11 which are adapted to aline with each other.

These holes are arranged near one edge of the folded material, preferably the folded

edge 8, and they are formed by partially detaching portions of said sheet material and the material detached in this manner is bent laterally of the face of each section at 12 and 6 in opposite directions to each other, thereby forming a thickened section or reinforcement 17 along one edge of the hole 11. The extremities 13 of the portions 12 of the material which are partially detached from 61 the sections 9 and 10 are then bent toward the edge 8 and said extremities are then forced against the adjacent faces of the sections 9 and 10 so as to cover said extremities.

The portions of the sections 9 and 10 along the sides opposite to the folded edge 8 may be perforated as at 14, 14 to receive screws or rivets, whereby said eyes may be attached to a case, trunk or the like. There are numerous ways in which eyes formed in 75 this manner may be utilized, for instance, in Fig. 1 a pair of eyes are employed as fastening means for a handle 15 constructed of sheet material which is looped through the holes 11 and fastened at 16. The rounded or thickened portions 17, when used in 80 this connection, will not chafe or cut the material constituting the handle 15 even though the material from which the eyes are formed is very thin.

When used as shown in Fig. 1 the sections 9 and 10 of the sheet material are preferably offset slightly at 18 so as to allow sufficient room between the edge, to which the handle is attached, and the adjacent portion of the 90 case to which said eye is attached. The eyes so formed may also be employed as handles without necessitating the use of the handle 15 and these eyes may be attached to the ends of trunks or chests in the manner shown in 95 Figs. 2 and 3, sufficient room being provided at 19 by offsetting the sections 9 and 10 at 20 to permit the fingers to be inserted through the holes 11 and through the space 19.

By forming the eyes of two substantially coextensive sections, as at 9 and 10, said eyes may be attached to the end of a strap or sheet of material 21, see Fig. 4, with the perforated edges of said sections 9 and 10 105 upon opposite sides of said sheet material, thereby providing a very strong handle.

In Fig. 5 an eye, embodying the invention hereinbefore described, is shown attached as a handle to the top of a case, in which instance the sections 9 and 10 are bent at 22 and 23 respectively in opposite directions

and the extremities so bent are attached by rivets or by other suitable means to the wall of the case.

It should be borne in mind, however, that the unessential details, such as the shape or design and the dimensions and furthermore the particular angles of the extremities of the sections 9 and 10 which are attached to the cases, trunks or the like, may be varied from the forms illustrated without departing from the spirit and scope of the invention.

Having thus specifically described my invention what I claim and desire by Letters Patent to secure is:

A device of the class described constructed of sheet material folded to form two sub-

stantially parallel coextensive sections, said sections having holes formed therein adjacent to the folded edge of said material by partially detaching portions of said sheet material therefrom, said partially detached portions of sheet material being curved laterally and outwardly from said sections in opposite directions and toward the folded edge of said material to form thickened edges along the sides of said holes nearest to said fold.

In testimony whereof I have hereunto set my hand in presence of a subscribing witness.

JOHN F. REILLY.

Witness:

SYDNEY E. TAFT.
